UNITED STATES PATENT OFFICE.

FREDERICK W. ROBERTSHAW, OF PITTSBURGH, PENNSYLVANIA.

THERMOSTAT.

1,387,618.

Specification of Letters Patent. Patented Aug. 16, 1921.

Application filed June 3, 1920. Serial No. 386,218.

To all whom it may concern:

Be it known that I, FREDERICK W. ROBERTSHAW, a citizen of the United States, residing at Pittsburgh, Allegheny county, Pennsylvania, have invented a new and useful Improvement in Thermostats, of which the following is a full, clear, and exact description, reference being had to the accompanying drawings, in which—

10 Figure 1 is a longitudinal sectional view of a thermostat embodying my invention; and

Fig. 2 is a section on the line II—II of Fig. 1.

15 My invention has relation to thermostats, and more particularly to thermostats of the general character described and claimed in my Patent No. 864,263, dated August 27th, 1907. In that thermostat the movable element consists of a rod of compressed carbonaceous material incased by a tubing usually of iron, steel, or other ferrous alloy. While the thermostats of my said patent have been highly successful in practice, and 20 have been used to a large extent, it is found that the carbon rod, when made of some grade of material, or with certain binding when subjected to high temperatures the carbon rod tends to disintegrate. Apparently, the cause for this disintegration is that the material of the rod has a greater affinity for oxygen than has the metal of the casing; and that when the parts are heated, the carbon rod absorbs oxygen from the casing. 25 However this may be, the fact remains that from some cause this disintegration of the carbon does occur.

I have discovered that this disintegration

can be largely prevented, and the life of the carbon element of the thermostat greatly extended, if a suitable protector is placed around the carbon and between it and the casing. For this purpose I have obtained excellent results by the use of a protector consisting of a tubing of copper. 40

45 Referring to the accompanying drawings in which I have illustrated one embodiment of my invention, the numeral 2 designates the rod of compressed carbonaceous material, 3 the outer casing and 4 the interposed copper protector. 5 designates any suitable device upon which the rod 2 is arranged to act.

The advantages of my invention result from the provision of a protector placed 55 around the carbon rod and between it and its casing which acts to greatly increase the life and effectiveness of the said rod.

I claim:

1. A thermostat comprising a non-expansible element composed of carbon, an outer metal casing for the same, and a protective covering of copper interposed between the rod and the casing, substantially as described. 60

2. A thermostat comprising a non-expansible element consisting of a carbon rod, an expansible metal element surrounding said rod, and a protective covering for said rod interposed between the said elements, 70 said covering consisting of a metal which will prevent chemical reaction between said elements, substantially as described. 65

In testimony whereof, I have hereunto set my hand.

FREDERICK W. ROBERTSHAW.
